UNITED STATES PATENT OFFICE.

OSCAR F. NILSSON, OF NEW YORK, N. Y.

GARMENT FASTENER.

1,404,471.

Specification of Letters Patent. Patented Jan. 24, 1922.

Application filed October 27, 1920. Serial No. 419,824.

To all whom it may concern:

Be it known that I, OSCAR F. NILSSON, a citizen of the United States, residing in the borough of Manhattan, city, county, and 5 State of New York, have invented a new and useful Improvement in Garment Fasteners, of which the following is a description.

This invention relates to garment fasteners and, particularly, to a two-part fastener adapted for use in connection with dresses, coats, waists, gloves, and other articles of apparel having plackets or openings to be closed or overlapping parts which are to be 10 temporarily secured together.

Among the objects of my invention may be noted the following: to provide a structure which obviates the use of, and eliminates, all springs, spring tongues, or other 15 similar yielding members usually utilized for snapping against or engaging a projection for securing the two members of the fastener together; to provide a structure which overcomes the many objections to the 20 so-called "dome" fasteners, or fasteners with rounded, flared, bulbous projections adapted to interact with sockets and receptacles to hold the two parts or members, and the parts of the garment to which they are 25 attached, together; to provide a simple, compact, strong and durable two-part fastener for garments, etc., the parts of which are readily interlocked and securely held against practically all strains, pulls and jerks, re- 30 gardless of the manner in which the same are exerted; to provide a two-part garment fastener so constructed that the male member may be readily, quickly and effectively interlocked with the female member and 35 held in the final or locking position securely; to provide a two-part garment fastener the form and structural features of which are such that it may be economically produced with a few simple mechanical op- 40 erations and with dies and tools which are comparatively simple and cheap; to provide a two-part garment fastener so constructed as to overcome the present difficulties experienced in interlocking the two parts of fas- 45 teners wherein the opening of the female member has to be felt for and the parts brought into interlocking engagement without sight or view of the female member, the structure of my two-part fastener obviating 50 55 the foregoing difficulties and providing for the engagement of the connecting members

by a sliding operation which practically leaves in view the female member, so that the user can readily see what he is doing; to provide a two-part garment fastener which 60 does not require pressure upon the two parts to force them together, but which are interlocked by a relative sliding action of the parts in planes parallel with each other and with the surface of the article to which the 65 fastener parts are applied; to provide a two-part garment fastener which is not liable to be crushed or distorted during the process of laundering the article to which the fastener is attached and which is so constructed 70 as to withstand great pressure and which, if slightly crushed or bent or distorted, (such condition usually putting other fasteners out of use) will, nevertheless, be able to perform 75 its functions and securely hold the parts of the garment together without liability to accidental separation.

With the foregoing objects in view, and others which will be detailed during the course of this description, my invention consists in the parts, features, elements and combinations thereof hereinafter described and claimed.

In order that my invention may be clearly understood, I have provided drawings 85 wherein:

Figure 1 is a top plan view of the female member of a garment fastener embodying my invention;

Figure 2 is a sectional view substantially 90 on the line 2—2, Figure 1;

Figure 3 is a top plan view of the male member of my garment fastener;

Figure 4 is a sectional view substantially 95 on the line 4—4, Figure 3;

Figure 5 is a central, sectional view of the two members of Figures 1 and 3, interlocked or in functional position, the section being taken at a right-angle to the line 2—2 of Figure 1;

Figure 6 is a top plan view of a different form of male member embodying my invention;

Figure 7 is a sectional view substantially 100 on the line 7—7 of Figure 6;

Figure 8 is a top plan view of another form of female member having a form of spring seat embodying my invention;

Figure 9 is a sectional view on the line 9—9 of Figure 8;

Figure 10 is a plan view of another form 110 of male member embodying my invention.

Referring to the drawings, the numeral 1 indicates the base of the female member of my fastener, which base, as seen in Figures 2 and 5, is formed approximately concavo-convex or dish-shaped, this form giving to the structure the additional strength required by reason of the removal of the material in producing perforations, apertures or openings 2 through the medium of which 10 the base is secured in functional position, the said dish-shape also enabling thick material to be received therein without lifting or raising the base in an unsightly or unseemly manner on the surface of the material to which it is applied. The openings 2 can be of any desired shape and as numerous as found expedient, depending upon the structural features of the member. The base 1 is provided with two oppositely disposed receptacles produced, in this instance of my invention and preferably, by striking up the body of the base to provide overlying or overhanging wings 3 free along their entire inner edges 4 from the material 20 of the base, but attached along their entire outer edges or walls 5 to the base. Being thus struck up, the wings 3 are substantial and strong and provide guideways for the elevated or projecting portions of the male 25 member presently described. As will be seen in Figure 1, the edges of the wings form acute angles at opposite ends and the outer terminals or ends 6 converge toward each other, while their inner ends 7 diverge from 30 each other, the edges of the latter being greatly flared outwardly from each other so as to produce a wide-open passage for the admission of the elevated or projecting portion of the male member. This arrangement 35 also has reference to the bodily disposition of the wings 3; that is to say, the wings, as a whole, are arranged to converge from inner to outer ends so as to produce an approximately V-shaped socket between and under 40 the wings 3 for the reception of the male member of the fastener. The expressions "outer ends" and "inner ends" are here used with reference to the terminals and entrance ends of the oppositely disposed wings 3, 45 which are arranged on opposite sides of a center line represented by the section line 2—2. Thus an exceedingly wide space or entrance end is provided for enabling the male member to be inserted into the female 50 member without feeling or searching for said entrance and enabling the members to be interlocked quickly and with great facility by a sliding action. By reason of the converging arrangement of the wings 3, together with their curved, outer, attached edges 55 5,—which edges are not struck from the same center but converge toward each other,—the male member is limited in its movement relatively to the female member and is caused 60 to interact with the wings so as to prevent 5—

any possibility of accidental displacement of one of the members relatively to the other. It should be understood, however, that the form of the wings 3 is such as to avoid any wedging action upon the male 70 member, since the curvature of the walls 5 at their outer ends is substantially concentric with the curvature of the male member, as will presently appear, and the edges 4 are substantially parallel. The base 1 also has 75 struck up therefrom a teat or projection 8, arranged eccentrically to the base, which preferably is a disk, though the form of the base may be angular or any other suitable shape. The teat 8 is a frictional device and 80 is preferably arranged midway between the inner edges 4 of the wings 3, and between the terminals 6 and the center of the base 1. While the teat 8 may be circular in general form, as shown in Figure 1, it is not a semi- 85 sphere. On the contrary, as shown in Figure 2, the surface of the teat has, approximately, a blunt V-shape with a slightly longer surface toward the center of the base 1 than in the opposite direction. This 90 form of teat makes a strong and effective retainer for the male member and provides for easy passage of the male member. The teat 8 may have any desired general outline. 95

The male member consists of a base 9, the form of which is shown as a cupped or concavo-convex disk, but which form will be changed to correspond with the form given to the base 1, if desired. Said base 9 is 100 provided with a plurality of attaching apertures 10, of any suitable form and location, and has struck up from its center a circular projection attached at opposite points to the base 9 by radial members 11, which serve 105 to strengthen the projection and maintain it rigidly in its elevated position. Of course, the radial members 11 are integral with the base 9 and the projection, and, by reason thereof, there is no angle or sharp edge or 110 projection which would snag or catch in lace, or sleazy, or light materials, of which ladies' shirt waists and other garments are usually composed. The projection is provided centrally with a circular depression 12 affording a receptacle for the teat 8 of the female member, which teat, in approaching the depression 12, slides frictionally over the surrounding, circular, flattened surface 13 of the projection of the male member between 115 the depression 12 and the radial members 11, the said teat 8 snapping into the receptacle 12, as it passes the elevated surface 13. Thus the user is enabled to determine when the male member has sufficiently entered the female member and is properly seated therein. The radial members 11, being opposite each other, and centrally disposed relatively to the projection, form, diametrically of the base 9, elongated leaders adapted to direct 120 125 130

the male member into the female member of the fastener; that is to say, it is only necessary that one or the other of the radial members 11 shall engage one or the other edge 5 7 of the respective wings 3 of the female member to enable the male member to be properly directed into the female member and readily and quickly seated in the latter by causing the teat 8 to snap into the depression 12 of the male member. Thus the importance of the flared edges 7 and the converging edges 5, and their terminals 6, can be readily realized, and, coupled with these 10 features, is the diverging disposition of the wings 3 and the location and form of the teat 8 so that the latter may slide frictionally across the elevated, circular, flattened surface 13 of the projection before the male member is set in the female member. I desire 15 to lay stress upon these features of my invention, since they are important and produce the various good results attributable to my fastener and overcome the various faults and objections to the usual form of fasteners heretofore referred to. The form of 20 the teat 8 is such that its shorter outer wall 8^a, being more abrupt, provides a substantial check against withdrawal of the male member, it requiring a substantial pull to 25 effect separation, while the longer inner wall enables the easy passage of one or the other of the members 11, it being understood that the male member 9 is reversible. The edges 14 of the projection are struck from the 30 same center and are substantially of the same curvature as the outer ends of the edges or walls 5, thus avoiding any wedging action between the members. It will be noted also, and this is another feature upon which I 35 desire to lay stress, that the two members of my fastener, when coupled as shown in Figure 5, have slight rotary movement the one upon or relatively to the other; that is to say, by reason of the radial members 40 45 50 55 60 65 70 75 80 85 90 95 100 105 110 115 120 125 130 giving diametrical elongation to the projection, the male member may swing or rotate in the female member to a limited extent when the projection is once set with the teat 8 in the depression 12, due to the edges 4 near the converging terminals 6 cooperating with the opposite edges of one of the radial members 11, the opposite circular portions of the projection underriding the wings 3 and engaging the walls 5. The connection thus brought about is a loose one and not fixed and rigid, since the parts may play upon each other to the extent of the difference between the diameter of the recess 12 and the diameter of the teat 8, or the difference in width of members 11 and distance between edges 4. The form of the teat also provides for quick separation of the members by a short relative movement.

In the form of my invention shown in figures 6 and 7, I have provided the male

member with a circular, centrally disposed, tubular, flanged projection 15, this form of projection for cooperation with the socket member 1 enabling the two members to have rotation relatively the one upon the other. 70 With this form of male member the flat flange 16 underrides the wings 3 of the female member, and the teat 8 frictionally engages the flat surface of the flange 16 and snaps into the central aperture of the projection 15. The form of the base may be the same as that shown in Figures 3 and 4 and is given a like numeral 9, the securing apertures also being indicated by 10. This form of my invention enables the connection to be loose and yet strong, and has practically all the advantages of the figure 3 construction.

The forms of my invention shown in Figures 8 to 10 are particularly useful and important when embodied in large and strong fasteners and when made of heavy materials having comparatively little inherent elasticity or resiliency. Such forms produce ease and facility of action between the parts 85 when brought or moved into interlocking engagement.

In the form of my invention shown in Figures 8 and 9, the female member has its base 1 of the same shape and form as in Figure 1, and the securing apertures 2 are similarly disposed. The wings 3 are shaped and disposed and produced in the same manner and are indicated by like numerals. In this form of my invention, however, the teat 8 is at the end of a spring or resilient tongue 17, produced by cutting out the metal of the base 1, the cut being in continuity with the cuts made in striking up the wings 3. The mounting of the teat 8 on a spring 105 tongue, as shown, makes the female member more pliable and responsive to the action of the male member, and the structure is quickly produced.

In Figure 10, I have shown a form of male member similar to that of Figure 3; but, having the radial members 11 provided with elongated grooves 21 for the easy passage of the teat 8 on the female members; and the raised portion or projection has an aperture 22 instead of a depression. In this form the securing apertures are differently placed in order to avoid weakening the metal. In fact, in all forms of the several members, the apertures 2 are disposed and the number is gaged according to the structure so as not to weaken the disks of the members.

Having thus described my invention, what I claim and desire to secure by Letters Patent is:

1. A garment fastener having, in combination, male and female members, the latter having a pair of oppositely disposed, converging wings providing between them at

- one end a flared entrance and, at the other end, parallel walls forming a guide, and the male member having a circular projection provided with radial members adapted to 5 slide between the wings, the female member having a teat arranged between the two wings, and the projection of the male member having a depression for receiving the teat.
10. 2. A garment fastener composed of a body member having a central projection provided with inclined radial members extending to the body member, and also having a central depression for receiving a teat, and 15 the radial members each being provided with an elongated groove.
3. A garment fastener composed of a body member having a central, circular projection provided with radial members extending toward the edge of the body member, and also having a central depression for receiving a teat.
20. 4. The combination of elements such as recited in claim 1 wherein the circular projection is provided with flanges on opposite sides adapted to underride the wings of the female member and cooperate with the converging walls of the wings.
5. A garment fastener comprising male 30 and female members, the male member being provided with a raised flange, the female member being provided with a pair of oppositely disposed raised guiding wings, the inner edges of which are free and the outer walls of which converge throughout their 35 length toward each other and constitute a guide and a stop for the edge of the flange of the male member to direct and limit the movement of the latter, and a teat arranged 40 between the wings in the space between their ends.
6. A garment fastener member made of a single piece of metal having securing means near its circumference, and wings struck up 45 therefrom having adjacent inner guiding edges and along their outer margin guiding walls arranged in converging relation so as to constitute a stop at one end to limit the movement of the male member, and a retaining teat also struck up therefrom and arranged between the guiding wings in the 50 space between their ends.
7. A garment fastener member made of a single piece of metal having securing apertures 55 therein near its circumference and guiding wings struck up therefrom and arranged in converging relation so as to constitute a stop at one end to limit the movement of a male member, and a retaining teat also struck up therefrom and arranged between the guiding wings in the space between their ends, and the body of the said member being provided with an elongated aperture extending from near one edge thereof between 60 the wings to a point toward the teat of the 65 said member so as to provide a resilient support for the teat.
8. A garment fastener member having guiding wings offset from the surface thereof and having guiding walls along their outer margins arranged throughout their length in converging relation to each other so as to constitute a stop at one end to limit the movement of the male member, the said wings having their inner free edges flared 70 outwardly at one end to provide a wide entrance between the two, and a teat provided on the member in the space between the wings adjacent their opposite end portions and offset from the center of said member.
9. A garment fastener member formed of a single piece of metal concavo-convex in cross-section, said member having securing apertures arranged about its edges and within the bounds of the securing apertures being provided with guiding wings offset from the body of the member, the said wings having marginal guiding walls arranged to converge toward each other, and straight inner guiding edges, and a securing teat arranged 85 in the space between the wings and offset from the center of said member.
10. A garment fastener member comprising a concavo-convex piece of metal provided with securing apertures and having 90 centrally thereof a raised portion provided with radial members at opposite sides, the said raised portion having a flat frictional surface and a recess for receiving a retaining member.
11. A garment fastener member made of a single piece of metal having securing apertures therein, and guiding wings struck up therefrom and arranged in converging relation, and a retaining teat also struck up 95 therefrom and arranged between the guiding wings, said teat having one side provided with a long inclined surface and the opposite side provided with a short inclined surface, the said surfaces converging from 100 bottom to top of the teat.
12. A garment fastener member having a central, offset, circular, flanged portion, and oppositely disposed radial guiding members extending from the flanged portion to the 110 body of the fastener, and means for securing the fastener to a garment.
13. A garment fastener member having a pair of oppositely disposed, converging, offset wings formed by stamping up and cutting the material of the member, the latter also having between the wings a retaining teat formed on a resilient portion of the member produced by cutting out an elongated portion from centrally between the 115 wings to near the edge of the member.
